COMBINATION LAWN TRIMMER AND EDGER

George D. Berdan, Fort Worth, Tex.

Application July 19, 1955, Serial No. 37,029

Term of patent 14 years

(Cl. D40—1)

FIG. 6.

FIG. 7.

Figures 2, 3, 4 and 5 are, respectively, fragmentary top, bottom, side and front views of the combination lawn trimmer and edger shown in Figure 1;

The handle is shown broken away for convenience of illustration in Figures 2 through 7, inclusive.

I claim:

The ornamental design for a combination lawn trimmer and edger, substantially as shown.
